FRONT PANEL FOR A REMOVABLE DRAWER
ASSEMBLY THAT HOUSES ELECTRONIC
DEVICES

Robert P. Gersin, New York, N.Y., assignor to Electro-
Mechanical Research, Inc., Sarasota, Fla., a corpora-
tion of Connecticut

Filed Feb. 27, 1967, Ser. No. 5,969

Term of patent 14 years

(Cl. D26—1)

FIGURE 1 is a front view of a front panel for a removable drawer assembly that houses electronic devices showing my new design;

FIGURE 2 is a right end view of the panel;

FIGURE 3 is a left end view of the panel; and

FIGURE 4 is a perspective view of the front panel.

The fragmentary broken line portion of the housing is shown for purposes of illustration only.

I claim:

The ornamental design for a front panel for a removable drawer assembly that houses electronic devices, substantially as shown and described.
